WINDOW CLEANING DEVICE

Application filed December 3, 1930. Serial No. 499,658.

This invention relates to window cleaning devices, and has for its general object and purpose to provide a simply constructed and inexpensive device which may be manipulated and operated with a minimum of manual labor for the purpose of easily and quickly cleaning the panes of window sashes without requiring that the user shall stand upon the outer sill of the window in imminent risk of life or limb.

It is a more particular object of our invention to provide a window cleaning device embodying a suitable supporting frame attached to one end of a handle member, and a flexible endless support assuming the general outline of a polygon when attached to said frame for a washing or cleaning element adjustably mounted in said frame whereby any one of the surfaces of the cleaning element may be opposed to the window glass.

It is an additional object of the invention to provide an improved mounting of an endless motor driven flexible band or belt for the cleaning element together with means whereby the cleaning element may be very easily and quickly applied to or removed from said driving belt.

With the above and other objects in view, the invention consists in the improved window cleaning device, and in the form, construction and relative arrangement of its several parts as will be hereinafter more fully described, illustrated in the accompanying drawing, and subsequently incorporated in the subjoined claims.

In the drawing, wherein we have disclosed one simple and practical embodiment of our invention, and in which similar reference characters designate corresponding parts throughout the several views,—

Figure 1 is an end elevation of the device, a part of the handle member being broken away;

Fig. 2 is a side elevation thereof;

Fig. 3 is an enlarged vertical sectional view taken on the line 3—3 of Fig. 2;

Fig. 4 is a detail sectional view on an enlarged scale taken on the line 4—4 of Fig. 1;

Fig. 5 is a section taken on the line 5—5 of Fig. 4, and

Fig. 6 is a detail sectional view taken on the line 6—6 of Fig. 1.

Referring in detail to the drawing, 5 indicates a supporting frame for the cleaning element. This frame is preferably constructed of aluminum or other relatively light metal and consists of two similar end members of general T-shaped form, each of said members including a part 6 with which the part 7 is centrally and integrally connected. The parts 6 of the two end members are rigidly connected to hold said members in spaced relation to each other by the spaced parallel bars 8 which may be welded or otherwise permanently secured to said parts. In the opposite ends of the parts 6, the ends of rollers 9 are rotatably supported in suitable anti-friction bearings and a similar roller 10 is also mounted in anti-friction bearings provided upon the ends of parts 7. An endless driving belt 11 extending substantially the entire length of the rollers 9 and 10 has frictional driving engagement with said rollers. This belt may be of canvas, rubber or other suitable material.

The cleaning element indicated at 12 is also in the form of an endless sheet of felt, chamois, rubber, or other material, which may be readily slipped over and upon the outer surface of the driving belt 11 and removably held thereon by the elastic bands indicated at 13 which are engaged upon the opposite ends of the cleaning element to thereby clamp the same to the surface of the belt 11.

Each of the parts 7 of the end frame members is provided intermediate of its ends with an opening 14 to receive an attaching bolt 15 for an arm 16. This arm at one of its ends is provided with an annular series of teeth or serrations 17 surrounding the bolt receiving opening therein for locking engagement with complementary teeth or serrations 18 provided upon the outer face of the frame part 7. The inner face of this frame part is recessed to receive a rectangular head 19 on one end of the bolt 15. A clamping nut 20 of any suitable form is threaded upon the other end of this bolt for adjustment against

the arm 16 to retain the same in locked engagement with the frame part 7.

Each of the arms 16 at its other end is formed with a flat tubular part 21 to receive the ends of a suitable U-shaped bail member 22, said bail member being detachably secured in connection with the arms 16 by set screws indicated at 23. To the center of the bail member 22, one end of the handle section 24 is riveted or otherwise rigidly fixed. This handle section is adapted to be adjustably telescoped within the main handle section 25 and is fixed in its adjusted position by the set screw 26.

One of the end trunnions of the roller 10 is formed for connection with one end of a flexible drive shaft 27 which may be driven by a small powered electric motor (not shown).

In the use of the device as above described, it will be readily understood that by loosening the clamping nuts 20, the frame 5 together with the driving belt and cleaning element thereon may be readily adjusted as shown in dotted lines in Fig. 1 of the drawing so as to position one side of the triangular shaped cleaning element for proper engagement with the surface of the window pane in accordance with the position of the operator with respect to the window. Upon then starting the electric motor, the roller 10 is positively driven by the flexible shaft 27 as the operator manipulates the handle 25 and moves the contacting side of the cleaning device over the surface of the window pane. Thus, all parts of the endless cleaning element 12 are brought into contact with the surface of the glass. In the first operation, the cleaning element may consist of sponge rubber, fabric or other water absorbent material which is thoroughly saturated. After the use of this water saturated cleaning element, it may be easily and quickly removed by simply loosening the set screws 23 to detach the bail 22 so that arms 16 may be swung downwardly parallel to the frame parts 7. The elastic bands 13 are then removed so that the endless cleaning element can be laterally shifted from the drive belt 11 over one end of the frame. A dry cleaning element of felt, rubber or other material is then applied upon the surface of the drive belt 11 and held thereon by the elastic bands 13, after which the bail member 22 is again connected with arms 16. Upon operation of the device with this drying element engaged with the surface of the window glass, the water thereon will be absorbed or removed.

In instances where electric power may not be available, or it is not desired to purchase a motor, the device may be used with the cleaning element stationary with respect to the supporting frame therefor, since by reason of the adjustment of this frame, when one side of the triangular shaped cleaning ele-

ment becomes more or less clogged with dirt, another side thereof may be easily and quickly positioned for engagement with the window glass. Since these endless cleaning members will be comparatively inexpensive, several of them can be kept on hand so that when one of them becomes unusable due to accumulations of dirt, it may be easily removed and a new one applied to the flexible belt or band 11. Thus, it will be apparent that a window cleaning device of the above description will be very economical in use. The adjustment of the polygonal shaped cleaning element also enables the user to readily manipulate the same over the outer surface of the window glass by means of the handle member 25 without leaving the room, thus avoiding the necessity of standing upon the window sill with the accompanying danger of a fall resulting in serious injury or death.

The various mechanical parts of our invention as herein disclosed, are exceedingly simple in form so that they can be produced at comparatively small manufacturing cost. We have shown and described an embodiment of the invention, which will be very efficient and reliable in practical use. Nevertheless, it is to be understood that as to the essential features thereof, the same may also be incorporated in various other alternative structural forms, and we accordingly reserve the privilege of resorting to all such legitimate changes therein as may be fairly incorporated within the spirit and scope of the invention as claimed.

We claim:

1. A window cleaning device comprising an adjustable handle, a T-shaped frame in connection therewith, having rollers at the free ends of said frame, an endless cleaning element mounted on the rollers of said frame and assuming a polygonal form thereon, and means for adjustably mounting said frame upon one end of the handle whereby one of the faces of the cleaning element may be disposed in position for engagement with the window glass.

2. A cleaning device comprising a handle, a T-shaped frame demountably connected to said handle, a removable cleaning element mounted on said frame forming a plurality of wiping faces around the frame, supporting arms for the frame, a bail member fixed to one end of the handle, means for detachably connecting the ends of the bail with said supporting arms, and means adjustably mounting said frame between the supporting arms whereby any one of the faces of the cleaning element may be disposed in position for engagement with the window glass.

3. A window cleaning device comprising a handle, a T-shaped frame mounted upon one end of said handle, spaced rollers mounted in said frame, an endless belt engaged upon said rollers, said belt assuming a polygonal

shaped form on said frame, means for clamping an endless cleaning element upon the surface of the belt, and a flexible driving connection with one of said rollers.

4. A window cleaning device comprising a handle, a frame, an endless belt mounted in said frame, a cleaning element removably carried by said belt, drive means for said belt, and means detachably connecting said frame with one end of said handle, said means including frame supporting arms, and means adjustably connecting said arms with the frame to position the cleaning element relative to the handle member for engagement with the surface of the window glass, said means being disconnectible whereby the cleaning element may be removed from the driving belt.

5. A window cleaning device comprising an adjustable handle, a T-shaped frame containing rotatable members at its free end portions, an endless belt mounted on said frame and carried by said rotatable members and forming a polygonal outline thereon, and means for detachably connecting said frame with the handle whereby to change the position of the frame about said handle.

In testimony that we claim the foregoing as our invention, we have signed our names hereto.
